SWITCH

James W. Woolf, Franklin, Pa., assignor to Joy
Manufacturing Company, Pittsburgh, Pa., a
corporation of Pennsylvania

Application September 18, 1948, Serial No. 49,921

9 Claims. (Cl. 200—5)

1

This invention relates to switches, especially to a pedally operated switch such as may be used in certain special automotive applications, as, for example, mine shuttle cars.

In any mechanized industry it is highly desirable to cut the idle time of equipment down to a minimum. Time during which equipment has to be out of use because of maintenance involves a loss of the use of the capital invested in the equipment for the time that the equipment is idle. It is accordingly advantageous in any mechanized industry to have equipment which is designed for easy maintenance with as little shutdown time as possible, in order that the investment represented in the equipment may not be idle any longer than necessary. To this end, the equipment should be designed as simply as possible for quick and easy maintenance when required.

It is an object of this invention to provide a switch for electrical equipment which is easily and quickly disassembled and repaired. It is also an object of this invention to provide a switch which is simple and rugged and which can be manufactured and assembled for a minimum cost.

These and other objects are accomplished in a simply constructed switch which requires only a few simple operations to get it apart for repairs, and which is quickly and easily reassembled. Parts of the switch are mounted on blocks and can be removed as units by removal of the blocks. In the course of switch actuation, the contacts which make and break the circuit have a wiping action which assures good contact. Spring biased means are provided to return the switch to neutral or switch-open position upon release of the actuating force.

In the drawings:

Fig. 1 is a view of a switch made according to the invention with the end cover removed and with parts broken away and in section substantially on line 1—1 of Fig. 3.

Fig. 2 is a side elevation of some portions of the switch mechanism with parts broken away and in section in order to better display the switch structure.

Fig. 3 is a view in section on line 3—3 of Fig. 1.

Fig. 4 is a front elevation view of the switch showing the mechanism for holding the actuating means in the switch off-position.

Fig. 5 is a schematic diagram of the stationary and movable contacts and their relationship to each other for the various switch positions, and

Fig. 6 is a partial front elevation showing a

2

modification of means for controlling the switch actuator.

A casing 2 is shown as having a plurality of mounting ears 4 for securing the casing to a piece 5 of equipment on which it is to be used. The casing has an end wall 6 which is provided on its inside surface with two threaded openings 8 and with a bearing boss 10. Four identical blocks 12 of electrically non-conductive material and having flanges 13 at one face thereof are secured in place on the inner surface of wall 6 by means of two threaded members 14 engaging the holes 8. The blocks are assembled in the switch with their flanges at opposite ends of each assembled pair.

15 As is best seen in Fig. 1, the blocks 12 are preferably hollow and generally resemble an isosceles triangle with a central rib 16. One of the threaded members 14 passes through the blocks near what would be the intersection of the two 20 equal sides of the triangle and the other threaded member 14 passes through the blocks near the intersection of the base and the rib 16 perpendicular to the base of the triangle. The four blocks 12 are divided up into pairs in which each 25 pair supports on each of its equal sides, between the flanges 13, a yieldable contact, indicated generally at 18.

In each contact 18, a contact finger 20 is secured to a hinge member 22; as is shown in the 30 drawings, the contact finger 20 may be clamped between the hinge member 22 and a conductor bar 24 by means of screws 26. The hinge member 22 is recessed as shown at 28 to receive a hinge pin 30. The pin 30 is carried on a bracket 32 35 which has a base 34 mounted on the non-conductive blocks by means of screws 36. The screws 36 extend through holes in adjacent insulating or non-conductive blocks. The center lines of the holes lie in the boundary plane between the 40 two blocks, so that half of each hole is in each block. The screws 36 do not thread into the insulating blocks themselves, but are threaded into holding members 38 inside the hollow insulated blocks 12. There are two members 38 for each 45 pair of blocks (one for each equal side) and each member lies adjacent the inside surface of one of the equal sides, clamping a pair of adjacent blocks between it and the base 34 by means of the screws 36.

50 A spring 40 is placed in compression with its one end around a screw 36 and against the base 34 of bracket 32, and its other end against the upper end of hinge member 22. Thus the spring 40 biases the hinge member and accordingly the 55 entire yieldable contact toward the axis of ro-

tation 42 of a movable contact, indicated generally at 44. The extent to which each yieldable contact 18 may be biased in the direction of movable contact 44 is limited by an abutment 43 provided at the lower end of the base 34 of bracket 32. A flexible conductor strip 48, of braided copper or the like, completes an electric circuit between the conductor bar 24 and an electric terminal 50. The terminal 50 is held in place by the upper one of screws 36 and is in good electrical contact with the strip 48.

The movable contact 44 is here shown as having limited rotational motion about an axis 42 referred to above. Movable contact 44 consists of a first contact element 52 and a second contact element 54. As is best seen in Fig. 3, the movable contact 44 is mounted on a shoulder 56 of a non-conductive hub 58. In order that the hub 58 and movable contact 44 may be rotated together without relative rotation between the two, the central opening in the web 60 of the movable contact is preferably made of a polygonal shape, such as a hexagon, and of course the shoulder 56 is made of a corresponding configuration. Similarly the central opening 62 in the hub 58 is also preferably hexagonal to cooperate with the head 64 of a drive pin 66. The drive pin 66, hub 58, movable contact 44, and insulating or non-conductive bushing 68, and a collar 70 are held in assembled relation by means of a bolt 72 which is threaded into the right-hand end of the drive pin 66. As is evident from Fig. 3 of the drawings, the web 60 of the movable contact is clamped between the non-conductive bushing 68 and a cooperating flange 74 on the hub 58. The collar 70 fits in a counterbore 76 in the non-conductive bushing 58 and thereby transmits the holding force of the bolt 72 to the bushing 58.

The drive pin 66 is keyed, as shown at 78, to an actuator 80. The actuator 80 is slotted, as shown at 82 of Fig. 4, and the hub 84 of the actuator is tightly clamped about the drive pin 66 by means of a clamping bolt 86 extending across the slot 82. The actuator 80 carries a projection 88 extending inward toward the end wall 6 of the casing 2. An outward extending projection 90 on the casing 2 serves as a stop member for the centering means described below.

Two rocker arms 92 and 94 are mounted to 50 pivot on the hub 84 of actuator 80. The upper arm of rocker 92 is connected to a spring 96 and the upper arm of rocker 94 is connected to a spring 98. Springs 96 and 98 are in tension, being mounted at their upper ends on bolts 100 and 102 respectively. As is best seen in Figs. 2 and 3, bolts 100 and 102 provide clearance between their inner faces and the end wall to avoid pinching or clamping the ends of the springs; the latter are thereby permitted such limited rotational movement about the bolts as may be required by angular changes of the spring axes.

The spring 96 biases its connected rocker arm 92 clockwise, so that the lower arm of rocker 92 is biased against the right edge of stop projection 90, as seen in Fig. 4. At the same time, of course, rocker arm 92 brings pressure to bear against the projection 88 on the actuator 80. Similarly spring 98 biases its rocker arm 94 counterclockwise, so that the lower arm of rocker 94 is biased against the left edge of stop projection 90, as seen in Fig. 4, and at the same time the rocker arm 94 brings pressure to bear against the projection 88 on the actuator 80. Thus the two rocker arms 92 and 94 with their respective

5 springs 96 and 98 form a centering device for the actuator 80, tending to hold the actuator in the position shown in the drawings, which is the neutral or open circuit position for the switch inasmuch as in this position the movable contact 44 and the pivotable contacts 18 are out of engagement.

As will be well understood by those skilled in the art, the power connections for the switch may be brought into the casing by means of a cable 104 passing through a tangential opening 106 in the casing 2. The connections per se from the power cable 104 to the various terminals form no part of the invention and are neither shown nor discussed in detail here.

In order that the switch parts may be completely enclosed, a cover plate 108 is provided for the end of the casing opposite the end plate 6. As can be seen in Figs. 2 and 3, the cover plate 108 is preferably threaded in place and is secured against unscrewing by means of at least one lock screw 110; a wire 112 passes through openings in the cover 108 and in the screw 110 and is preferably held together by means of any suitable seal 114.

Fig. 6 shows an alternative design for control of the actuator, designated 180 in this embodiment. In Figs. 1 to 4 inclusive, the actuator 80 is automatically returned to the switch-open position upon the release of any force applied to the actuator. In the embodiment shown in Fig. 6, the actuator 180 is provided with a notched sector 183 which cooperates with a holding device, indicated generally at 185. The holding device consists of a bracket 187 having a cylinder 189. A piston 191 is reciprocable in cylinder 189 and compresses a spring 193 between its upper end and the upper end of the cylinder. A small opening 195 in the upper end wall of the cylinder assures free movement of the piston 191 without interference from entrapped air. The lower end of the piston 191 carries a roller 197 which cooperates with the notches in the sector 183 to hold the actuator 180 in any selected one of a number of operating positions. A handle 199, threaded into the upper end of piston 191 extends through the end wall of the cylinder 189 and enables an operator to move the piston 191 in its cylinder without moving the actuator.

Operation

To facilitate a discussion of the operation of the switch of this invention, the yieldable contacts all referred to generally by the reference numeral 18 in the above discussion are given individual reference characters A, B, C, and D. The circuit diagram of the movable and yieldable contacts shown in Fig. 5 is merely a developed view of the structure shown in mechanical detail in Fig. 1. It is as though the movable contact 44 had been split radially inward from the contact element 54 approximately along the line 3-3 of Fig. 1, and spread out to provide the diagram shown in Fig. 5.

To put the vehicle controlled by this switch into low speed-forward, the actuator 80 is moved counterclockwise, as seen in Fig. 1, to the first operating position, in which the contact element 52 engages yieldable contacts A and B. In this first operating position, only the yieldable contacts A and B are engaged by the movable contact 44. In order to move the switch into high speed-forward, the operator continues the counterclockwise movement of actuator 80 to the second operating position. In this second posi-

tion, yieldable contacts A and B remain in engagement with the contact element 52 and the contact element 54 engages the yieldable contact D. The connections are thereupon effected for high speed-forward.

In moving the actuator 80 counterclockwise as seen in Fig. 1, clockwise as seen in Fig. 4, the operator causes the clockwise rotation of rocker arm 92 to increase the tension in spring 98. As the actuator 80 is moved clockwise in Fig. 4, the projection 28 on the actuator moves away from the lower end of rocker arm 92. Rocker arm 92 is not able to follow the clockwise motion of actuator 80 because its lower arm also engages the fixed stop or projection 90 on the casing. Thus when the actuator 80 is released the increased tension in the spring 98 serves as a restoring force to return the actuator 80 to the switch-open position.

From this switch-open or neutral position, the switch may now be moved into low speed-reverse by moving the actuator 80 clockwise, as seen in Fig. 1. When the movable contact 44 is moved into the first operating position in the reverse direction, the contact element 52 engages the yieldable contact C; the yieldable contact D is not engaged at this time by the contact element 52, because contact element 52 is recessed or cut away, as shown at 116 in Fig. 5. However, the contact element 54 engages the yieldable contact B, so that in the low speed-reverse position of the switch the movable contact 44 engages yieldable contacts B and C. To shift the switch into high speed-reverse, the actuator 80 is moved still further clockwise, as seen in Fig. 1. Contact element 52 remains in engagement with yieldable contact C, and contact element 54 remains in engagement with yieldable contact B. In addition, contact element 52 comes into engagement with yieldable contact D. Accordingly, in the high speed-reverse position of the switch, the movable contact 44 engages yieldable contacts B, C, and D.

In moving contact element 80 clockwise as seen in Fig. 1, counterclockwise as seen in Fig. 4, the operator causes the projection 28 to move the rocker arm 92 counterclockwise, increasing the tension in spring 96. In a manner similar to that described above for the forward position, this tension in the spring 96 sets up a restoring force which returns the actuator 80 to the neutral or switch-open position upon its release.

When either contact element 52 or 54 engages any yieldable contact 18, that contact is caused to pivot slightly about its pin 30, compressing its spring 40. The engagement between the contacts is such as to have a wiping effect of the yieldable contact on the movable contact, with pressure between the contacts caused by the spring 40 insuring good electrical engagement.

The construction of a switch made according to this invention is such that the switch is readily disassembled and reassembled. After unscrewing the cover plate 108, the operator need merely remove the two screws 14 and disconnect the power leads from the terminals 50, in order to be able to remove the non-conductive blocks 12 in pairs and with them the yieldable contacts 18 in pairs. The movable contact 44 is readily removed simply by unscrewing the bolt 72.

The operation of the embodiment shown in Fig. 6 involves the engagement of the roller 197 in the different notches of the sector 183 for the various operating positions of the actuator.

It will be readily understood by those skilled

in the art that this invention provides a switch which is of a simple construction and is readily disassembled for maintenance and may be quickly reassembled with a minimum of idle time of the equipment. The switch is so constructed as to provide positive engagement between the contacts to insure good conductivity through the switch. Operation of the switch is simple and does not require a high degree of skill. Other advantages will be readily apparent to those skilled in the art.

While there is in this application specifically described two forms which the invention may assume in practice, it will be understood that these forms of the same are shown for purposes of illustration, and that the invention may be modified and embodied in various other forms without departing from its spirit or the scope of the appended claims.

What I claim as new and desire to secure by Letters Patent is:

1. In a switch, a casing, a pair of identical hollow non-conductive blocks removably mounted side by side in the casing, a first contact, means including a holding member inside said blocks for mounting the contact on the blocks, a second contact in the casing movable into and out of engagement with the first-named contact, and means including an actuator extending outside the casing for moving the second contact into and out of engagement with the first contact, and also including a projection on the actuator, another projection on the casing, a rocker arm pivotally mounted outside the casing, and a spring connected to bias the rocker arm into engagement with both of said projections.

2. In a switch, a casing, a pair of identical hollow non-conductive blocks removably mounted side by side in the casing, a pair of contacts, means including a pair of holding members inside said blocks for mounting the contacts on opposite edges of the blocks, a movable contact in the casing having a first and second contact element and being positionable into and out of engagement with the first-named contacts, and means including an actuator extending outside the casing for positioning the movable contact selectively into and out of conducting engagement with the first-named contacts, and including also a projection on the actuator, another projection on the casing, a pair of opposed rocker arms pivotally mounted so as to be engageable with both projections, and spring means connected to bias the rocker arms into opposed engagement with the projections.

3. The switch set forth in claim 2, in which the movable contact is mounted for limited oscillatory movement and the electrical conducting engagement of the movable and first-named contacts includes two positions of the movable contact in one of which said first contact element engages one of the first-named contacts and said second contact element engages the other of the first-named contacts, and in the other of which the engagement of the contact elements and the first-named contacts is reversed.

4. In a switch, a casing, a pair of electrically non-conductive blocks removably mounted side by side in the casing, a first contact, means including members passing between the blocks for mounting the contact on the blocks, a second contact in the casing movable into and out of conducting engagement with the first-named contact, an actuator connected to move the second contact into a selected position, and spring means

connected to bias the actuator into such a position that the contacts are disengaged, the last named means including a projection on the actuator, another projection on the casing, and a rocker arm biased into engagement with both projections. 5

5. The switch of claim 4, in which each of said blocks is provided with a peripheral flange at one face, the blocks being assembled in the switch with the two flanged faces at opposite ends, and 10 the first-named contact being mounted between the flanges of the pair of blocks.

6. An electrical contact mounting comprising a casing, a pair of identical hollow blocks, each block being substantially an isosceles triangle 15 having a hole at its vertex and another hole in its unequal side, means passing through the holes to secure the blocks in the casing with two adjacent faces thereof lying in a common contact surface, the mounted blocks having other holes there- 20 through with their axes lying substantially in said contact surface, electrical contact means, holding means inside the hollow blocks, and means engaging the electrical contact means and the holding means and passing through said 25 other holes to support the electrical contact means in operating position.

7. A mounting as in claim 6, in which each block has a rib extending from the vertex to the unequal side, the two first-named holes lying in the rib.

8. A mounting as in claim 7, in which each block has a peripheral flange, the electrical contact means being mounted between the flanges of the pair of blocks.

9. A mounting as in claim 6, in which each block has a peripheral flange, the electrical contact means being mounted between the flanges of the pair of blocks.
